GAME

Raphael A. Pilla, Philadelphia, Pa.

Application September 12, 1939, Serial No. 294,433

2 Claims. (Cl. 46—1)

This invention has to do with games and is concerned primarily with games of the type involving the progressive movement of a marker or counter.

5 At the present time there are available to the public various games including a "ladder" or "pathway" of success, and which games involve the movement of a counter or marker along the ladder or pathway. With the now known games 10 of this type the movement of the marker is controlled or actuated by devices that depend solely on luck or chance.

With this condition in mind this invention has in view, as an important object, the provision 15 of a game of the character above noted in which the movement of the marker or counter is controlled by a device involving skillful manipulation; the successful operation of the device depending not only on the player's knowledge of 20 the theory underlying the device, but also skillful manipulation of the same.

More in detail this invention has in view, as 25 an object, the provision of a game of the character above noted which includes a playing board that involves certain novel features.

More in detail this invention has in mind an arrangement in which the ladder or pathway is divided up into two main sections. In the lower or first section the counter or marker progresses 30 upon every successful manipulation of the playing device. When the player makes an unsuccessful attempt to manipulate the device, this failure is recorded on another portion of the card, and these failures or unsuccessful attempts must 35 be removed before progress can be made in the higher section of the ladder.

Yet another object of the invention is the provision of a game of the character above noted which includes a novel type of playing device 40 as the means for controlling movement of the marker. Along this line the invention has in view, as a further detailed object, the provision of a device comprising a stick and a strip of flexible material that may be wound about the stick, the stick being considerably longer than the strip of material.

In accordance with this invention the strip is first doubled on itself to form a bight which receives the stick. The double thickness of the 50 strip is then wound tightly about the stick until the entire double strip is so wound. The player now grasps the stick at either end without touching the fabric, and by manipulation attempts to so unwind the double strip that the bight will 55 shift from its original position of receiving the

stick to one at the side thereof so that when the unwinding is completed the fabric will fall free from the stick.

It is obvious that in order for the player to 5 successfully manipulate the stick to obtain the desired end he must either depend on luck, or have a knowledge of the windings of the strip about the stick.

Various other more detailed objects and advantages of the invention will in part become 10 apparent, and in part be hereinafter stated, as the description of the invention proceeds.

The invention, therefore, comprises a novel game including a playing card which carries a 15 ladder or pathway of success, and certain places where failures or disappointments may be scored. A counter is intended to be moved along the ladder or pathway of success which is included in the card, and the movement of the counter is controlled by a playing device that consists particularly of a stick, and a strip of flexible material 20 that is adapted to be wound thereabout, successful manipulation of the stick ending in an unwinding of the strip therefrom without the player touching the same with his hands. 25

For a full and more complete understanding of the invention reference may be had to the following description and accompanying drawing, wherein

Figure 1 is a plan view of a playing card which 30 is designed in accordance with the precepts of this invention.

Figure 2 is a side elevational showing of a stick with a strip of material wound thereabout.

Figure 3 is a view taken from the end with the 35 stick shown in section, the material being in the tightly wound condition of Figure 2.

Figure 4 is a view showing the stick and certain turns of the strip winding in an expanded relation.

Figure 5 shows the relative position of the 40 stick and the bight when the double strip of Figure 4 has been unwound.

Figure 6 is a view similar to Figure 4 but developing a change in the windings involving an 45 additional turn of a single thickness of the strip, and

Figure 7 is a view showing the relative position 50 of the stick and the bight when the strip in the condition of Figure 6 is unwound.

Referring now to the drawing, wherein like reference characters denote corresponding parts, a playing card which is intended to be an essential element of the present game is shown in 55 Figure 1 and identified by the reference character

A. This card may be made from any suitable material, such as cardboard, and as many of the cards A may be included in a single set as desired.

5 In order that the game may be more appealing to the players the card may carry a character which is associated with the attainment of success or a particular wish. Thus the jinni of Arabian mythology may be included on the card 10 A as one example of this idea. This fanciful character is designated 10, and within the outline of the same the card A carries a ladder or pathway of success which is identified in its entirety by the reference character 11. This 15 ladder or pathway of success includes a plurality of individual steps 12 which may carry appropriate designations for certain particular lines of endeavor.

It is important to note that the ladder of success 11 includes a dividing line such as indicated at 13, which marks off the steps 12 above and below said line. In the form of the invention illustrated in the drawing the ladder of success 11 includes various steps which might be associated with the advance of a young boy entering the employ of a bank. Each player must have a card of the general character indicated. Obviously this is intended purely for illustrative purposes, and is intended to be no limitation on the 20 invention.

30 A marker which is to be employed in conjunction with the ladder 11 is shown at 14, and on the occasion of the first successful manipulation of the playing device, which is hereinafter 35 described in detail, the player places this marker 14 on the lower-most step 12. On the occasion of every successive successful manipulation of the playing device this marker 14 may advance one step.

40 In order to facilitate progress during the early stages of the playing of the game, all successful attempts of the player to manipulate the playing device will result in a forward movement of the marker 14, this rule applying up to the dividing line 13.

45 However, all failures or unsuccessful attempts are intended to be recorded by placing a marker 14' in the appropriate scoring columns under "Wish Disappointments" which are designated 15. When five failures are so recorded no progress above line 13 can be made as a result of 50 successful manipulation until each block of five failures is cancelled by one successful manipulation; if less than five failures are on the score 55 each success entitles the player to advance one step above line 13, except that the final step may not be taken until all failures are removed.

60 Referring now more particularly to Figures 2 to 7, inclusive, the novel playing device of this invention will be described.

65 This device includes, as an essential element, a stick 16 which may carry at each end fanciful or ornamental characters which might have some relation to the pictorial representation on the 70 card A. For instance, in line with the jinni of Arabian mythology which is shown on the card A, the stick 16 might carry, at each end, representations of Aladdin's Lamp, which are designated 17.

75 A strip of material is shown at 18 as being of double thickness and tightly wound about the strip 16. Prior to winding of the strip of material 18 about the stick 16 the same is folded back on itself to form a double thickness terminating in a bight, such as shown at 19 in Figures

4 and 5. The double thickness strip is then tightly wound about the strip to assume the condition shown in Figures 2 and 3, which provides an inner layer 20 and an outer layer 21.

5 Referring now more particularly to Figure 4, it will be noted that if exactly the same number of turns are made by the inner and outer layers 20 and 21, respectively, the stick 16, for all effective purposes, remains in the bight 19 so that if the double thickness is completely unwound by 10 the player the bight 19 will catch the stick 16 in the manner depicted in Figure 5. Such a result would, in accordance with the theory of this game, be considered a failure or unsuccessful attempt, and would result in one scoring under 15 "Wish Disappointments."

20 Referring now more particularly to Figures 6 and 7 it will be noted that the outer layer 21 has been unwound for one turn in the direction of the arrows of Figure 4. At the same time 25 the inner layer 20 has not been so carried around. This results in a shifting of the bight from the location identified by the reference character 19 to that location marked 22. Thus when the double strip is completely unwound the bight 19 assumes the position at one side of the stick 16, as shown in Figure 7, with the result that the strip will fall away from the stick, this being the 30 result of successful manipulation by the player.

35 It is, of course, possible that a player might manipulate the stick and accidentally cause one layer to unwind without the simultaneous unwinding of the other layer for the same turn, and thus achieve the desired result more or less by chance. However, it is evident that a player 40 having a knowledge of the windings, and the manner in which the bight shifts from the location marked 19 to that designated 22, will be able to combine this knowledge with successful manipulation to more readily achieve the desired 45 result.

50 While various flexible materials may be employed for the strip 18, the invention has particularly in mind the use of an appropriate fabric. Also various types of ornamental features 45 may be included in the card A, fabric 18 or stick 16 to carry out any desired theme.

55 Preferably, each player chooses a card which best expresses his ambition. The number of playing sticks he has to manipulate each turn 50 he is allowed to play depends upon the number of steps in the ladder, that is, one stick for each step. The first player to reach "the top" is the 60 winner.

65 While a preferred specific embodiment of the invention is hereinbefore set forth it is to be clearly understood that the invention is not to be limited to the exact constructions illustrated and described, because various modifications of these details may be provided in putting the invention into practice within the purview of the 70 appended claims.

I claim:

1. In a game of the character described, a 65 playing device comprising a strip of flexible material comparable to a fabric and having a body capable of holding a roll formation, said strip being doubled on itself to form a bight with the strip of material defining two layers that are folded into a multi-turn roll, a member received in said bight and projecting from each side of said roll an appreciable distance and supporting said roll, said roll frictionally engaging said member whereby rotation of said member causes a corresponding rotation of said roll to shift the bight 70 75

in said strip whereby the strip may be caused to fall free from said member.

2. In a game of the character described, a playing device comprising a fabric strip having a body capable of holding a roll formation doubled on itself to form a bight and defining two layers, said strip being wound into a multi-turn roll with the bight at the center thereof, a stick re-

ceived in said bight and projecting from each side of said roll, said roll being supported by and frictionally engaging said stick whereby rotation of said stick causes a corresponding rotation of said roll to shift the bight in said strip, 5 and a handle element at each end of said stick.
